RECLINING CHAIR

Ralph M. Galloway, 601 S. Audubon Ave., Tampa, Fla.

Filed Mar. 30, 1960, Ser. No. 59,951

Term of patent 14 years

(Cl. D15—11)

The left side of the chair, not shown in the drawings, is a duplicate of the right side depicted in FIGURES 1 and 2.

I claim:

The ornamental design for a reclining chair, as shown and described.
